UNITED STATES PATENT OFFICE.

CHARLES W. TRICKEY, OF MCGRATH, MINNESOTA.

WINDOW SCREEN.

Application filed August 11, 1921. Serial No. 481,519.

To all whom it may concern:

Be it known that I, CHARLES W. TRICKEY, a citizen of the United States, residing at McGrath, in the county of Aitkin and State 5 of Minnesota, have invented certain new and useful Improvements in a Window Screen; and I do hereby declare the following to be a full, clear, and exact description of the invention, such as will enable others skilled in 10 the art to which it appertains to make and use the same.

This invention relates to means for preventing flies, mosquitoes, gnats, and winged insects from entering a room or like place 15 through a window opening when the sash is moved to permit of ventilation.

The invention consists of a screen, a spring roller having one end of the screen detachably connected thereto, the opposite 20 end of the screen being detachably connected to the sliding sash moved therewith and protective means for housing the parts.

Other objects and advantages will be apparent and suggest themselves as the nature 25 of the invention is understood.

While the drawing illustrates an embodiment of the invention it is to be understood that in adapting the same to meet different conditions and requirements, various changes 30 in the form, proportion and minor details of construction may be resorted to without departing from the nature of the invention.

Referring to the accompanying drawing forming a part of the specification,

Figure 1 is a front view of the lower portion of a window provided with a screen embodying the invention.

Figure 2 is a horizontal section on the line $x-x$ of Figure 1.

Figure 3 is a vertical section on the line $y-y$ of Figure 1.

Figure 4 is a detail view of the spring roller and parts of the screen attached thereto, and

Figure 5 is a further detail view.

Fig. 6 is a plan view of the supporting frame.

Fig. 7 is a vertical section showing the relation of the tongue 17 to the cover 13.

Corresponding and like parts are referred to in the following description and designated in the several views of the drawings by like reference characters.

The numeral 1 designates a window frame 55 of approved construction provided with a

sliding sash 2. A supporting frame is detachably connected to the sill of the window frame and comprises parallel longitudinal strips 3 and short connecting strips 4. The ends of the longitudinal strips 3 are upturned and apertured to receive the journals of the guide and spring rollers. Clips 5 are attached at one end to the sill of the window frame and extend over the longitudinal strips 3 and hold the supporting frame in 65 the required position.

A guide roller 6 is journaled in the upturned ends of the innermost longitudinal strips 3 with its inner side about in the plane of the sliding sash 2 whereby to hold 70 the screen 7 in proper position. A spring roller 8 is journaled in the upturned ends of the outermost strip 3 and is adapted to have the screen 7 wound thereon. The spring roller 8 is provided in its length with a plurality of hooks 9 which detachably engage slots 10 in a reinforced end of the screen 7.

The opposite end of the screen 7 is reinforced and provided with openings 10 to receive hooks 11 applied to a lower rail of 80

the sash 2. In this manner the screen 7 is both detachably connected to the sliding sash and the spring roller. Guide strips 12 are applied to the jams of the window frame and engage edge portions of the screen 7 to 85

prevent the formation of a space through which flies and other insects may find an entrance. The guide strips 12 consist of metal straps bent intermediate their longitudinal edges to provide angularly disposed 90 wings. One of the wings or flanges is attached to the window frame whereas the other flange projects outwardly therefrom to engage the vertical edge of screen 7 and prevent the formation of a space through 95 which insects may pass.

The supporting frame and the guide and spring rollers are enclosed by means of a cover which consists of a curved plate 13 having an offstanding portion 14 along a 100 longitudinal edge. The offstanding portion 14 preferably consists of a bar or strip riveted or otherwise attached to the cover 13 and having keeper 15 to receive the clips 5. Openings 16 formed in an edge portion of the cover 13 adjacent the offstanding portion 14 receive the clips 5. A tongue 17 projecting outwardly from the cover is adapted to receive a suitable fastening whereby the cover is made secure when in position. 110

Having thus described the invention, what I claim is:—

1. Means for screening a window the same comprising clips applied to the sill thereof, a supporting frame retained in position by means of said clips, a spring roller mounted upon the supporting frame, a screen wound upon the spring roller and detachably engaging the lower rail of the sash and a cover for the spring roller and supporting frame retained in position by means of the said clips.
2. Means for screening a window, the same comprising a spring roller, a screen wound on the spring roller, a supporting frame for the spring roller, clips applied to the sill of the window frame and engaging the supporting frame, and a cover for the spring roller and supporting frame therefor having an offstanding portion provided with keepers, said cover having openings in an edge portion adjacent its offstanding part to receive the said clips which also engage the keepers of the offstanding portions.
3. Means for screening a window, the same comprising a supporting frame including longitudinal strips having their end portions upstanding, clips secured at one end to the sill of the window frame and engaging the strips of the supporting frame, guide and spring rollers mounted in the upturned ends of the strips, a screen passing around the guide roller and wound upon the spring roller and detachably engaging the lower rail of the sliding sash, guide strips applied to the sides of the window frame and engaging the vertical edge por-

tions of the screen to exclude insects, a cover for the spring and guide rollers having an offstanding portion along one edge and provided with openings adjacent the offstanding portion to receive the said clips, keepers on the offstanding portion of the cover receiving said clips, and a tongue projecting from the offstanding portion of the cover and adapted to receive a fastening whereby the parts are made secure to the sill of the window frame.

4. A window screening means comprising a pair of spaced clips secured to the window sill, a supporting frame secured by said clips and said supporting frame comprising spaced strips having upturned perforated ends, a spring roller mounted by the outer set of perforated upturned ends, a guide roller mounted by the inner set of perforated upturned ends, and a window screen normally wound on said spring roller and having its free end attached to a window sash.

5. A window screening means comprising a pair of spaced clips secured to the window sill, a supporting frame slidably engaged by said clips, said supporting frame carrying bearings for a spring roller and a guide roller, a housing member secured by said strips and by an attaching leaf carried by said housing, said housing member when in position serving to prevent disengagement of said supporting frame from said clips.

In testimony whereof I affix my signature in presence of two witnesses.

CHARLES W. TRICKEY.
